PULVERIZING MILL AND THE LIKE

Application filed March 13, 1930, Serial No. 435,406, and in Great Britain March 14, 1929.

This invention relates to improvements in pulverizing mills and the like in which pulverization is effected by a plurality of balls cooperating with tracks.

5 The invention has for one of its objects the provision of means whereby more effective and regular grinding can be performed than is possible with known arrangements.

Another object of the invention is the provision of means whereby more effective discharge of pulverized material from the balls is obtained thereby enabling a pulverizing mill of higher duty to be produced than has been possible in the past.

15 Another object of the invention is the provision of means whereby more effective air currents are produced for conveying the pulverized material delivered from the rotary track to the delivery orifice thereby enabling 20 more efficient operation to be obtained.

A further object of the invention is an improved construction particularly adapted for the reduction of crushed coal into a powder of the fineness which is necessary when coal is 25 to be consumed in pulverized form.

A further object of the invention being the provision of means whereby the pulverized material delivered from the apparatus is more uniformly graded than has been usual 30 with apparatus of this type.

The invention consists in the arrangement of a plurality of balls in a rotating track, said balls being maintained therein by an elastically loaded nonrotary track; means for feeding crushed material to said rotating track to be pulverized; means for producing an annular stream of air for entraining the material delivered from said track, said stream of air conveying particles of the pulverized material of less than a predetermined mass to and through a delivery passage whilst the heavier particles are returned by the force of gravity to the rotating track for further pulverization.

45 In the drawings Figure 1 illustrates in sectional elevation one form of improved mill constructed in accordance with this invention;

Figure 2 is a plan view in section taken 50 on the line 2-2 of Figure 1;

Figure 3 is a fragmentary view in elevation showing the feeding means and some of the air inlets; and

Figure 4 is a fragmentary view illustrating the automatic separation of particles which takes place during the passage of the treated material from the bevelled edge to the delivery passage.

As illustrated in the drawings forming part of this specification the mill comprises a vertical shaft *a* supported upon a suitable ball thrust *b* and provided with worm and worm wheel gearing *c* to enable rotation of the shaft *a* to be effected although other means of rotation may be employed if so desired. The vertical shaft *a* is provided with a journal *d* at its upper end adapted to rotate in a bearing *e* formed in the upper part of the stationary structure *f* of the machine which also comprises a supply passage *g* for the admission of roughly crushed material, a delivery passage *h* for the pulverized material and an air inlet or air inlets *i*.

The roughly crushed material is supplied to the hopper *k* and is fed by the screw conveyor *l* through the tunnel *m* to the orifice *g*, the conveyor *l* being rotated at the required speed by means of the bevel wheels *n.n.* shaft *o*, crank *p*, lever *q*, pawl *r* and ratchet wheel *s*, such means being provided to prevent the admission of air through the hopper *k* as may be necessary.

Beneath the supply passage *g* a stationary circular serrated element *t* is located, the shaft *a* having feeder arms *u* and a conical toothed braker *v* at this point so that the material is forced by the feeder arms *u* between the serrations on the stationary element *t* and the teeth of the braker *v* means adapted to be sheared being provided, if necessary, should excessive torque be required from the shaft *a*.

The material delivered from the serrated element *t* is discharged on to a track *w* mounted on and rotated by the vertical shaft *a*.

A plurality of balls *x* of suitable diameter are arranged on the track *w* and maintained in position by a nonrotating ring element *y* suitably loaded by springs *z* or the like, the

number of balls w provided being insufficient to fill the track w completely so that a gap w^1 , see Fig. 2, exists between contiguous balls at one point. The dimension of the gap w^1 depends upon a number of conditions but in a general way when the track w is sufficiently long to accommodate a given number of balls w a single ball may be omitted. The configuration of a transverse section of the track w is such that the balls w engage therewith on a line extending substantially from a vertical plane to a horizontal plane said track w being continued upwards at its larger diameter so as to form a bevelled edge or fence w^1 .

In transverse section the configuration of the bevelled edge or fence w^1 is a portion of a paraboloid lying between two horizontal planes or approximates to such curve, the contour being so proportioned that the fuel whether ground or not is just able to run up said bevelled edge w^1 by centrifugal force.

In proximity with the bevelled edge w^1 and exteriorly thereof a stationary circular lip w^2 is arranged, the lip w^2 cooperating with an adjustable sleeve w^3 mounted on the cover f^1 of the stationary structure f so as to form an annular jet supplied with air from the air inlet i , the sleeve w^3 being raised or lowered by means of the finger operable nuts w^4 which cooperate with the screwed stems w^5 attached to said sleeve.

Owing to the location of the air inlets i the direction of flow of the air to the annular jet is fixed, the velocity and quantity of said air being independently controllable by varying either the area of the jet by raising or lowering the sleeve w^3 or by varying the speed of the fan exhausting air from the separator the base of which is indicated by the letter S in Figures 1 and 2.

In operation crushed material, for example, coal, is fed by the conveyor l through the supply passage g to the track w . As previously stated the track w is rotated at such a speed that the material under the action of centrifugal force can just pass up the bevelled edge w^1 . During the passage of the coal across the track w it is pulverized by the balls w and the delivery from the edge w^1 is entrained by the stream of air issuing from the annular nozzle formed by the lip w^2 and the sleeve w^3 and carried in the direction of the arrow 3 between the back of the ring element y and the inside surface of the cover f to the delivery passage h particles having less than a predetermined mass being conveyed through the passage h to the separator whilst particles of greater mass fall, as indicated by the arrow 4, under the action of gravity, and intermingle with the feed from the passage g , as diagrammatically illustrated in Figure 4.

When coal is being pulverized in such an apparatus the air supplied to the inlet may

be heated as desired in which case the air inlets i or some of them may be closed with suitable doors the heated air being supplied through the passage i^1 .

Obviously, certain variations may have to be introduced into the construction to enable a mill constructed according to this invention satisfactorily to pulverize different materials owing to the wide variations in the natural characteristics of such materials.

We claim:

1. An improved pulverizing mill having in combination a rotary track, an elastically loaded non-rotary track, a series of balls disposed between and travelling round said tracks, an annular suction passage round said tracks communicating with the external atmosphere, a beveled edge on the discharge periphery of the rotating track of the form of a paraboloid lying between two horizontal planes, a stationary circular lip in proximity with the said beveled edge and an adjustable sleeve sliding on the upper part of the mill and having an outwardly and downwardly projecting lip arranged to direct the suction air to meet the stream of pulverized material thrown out centrifugally and direct the combined stream in an upward and inward direction so that the heavier particles of solid material are returned by gravity to the inside of the said tracks for re-pulverizing.

2. In an improved mill as claimed in claim 1, a stationary serrated ring mounted in the supply passage of the mill, a rotating serrated element carried by the rotating track, and rotating feeder arms in the said supply passage adapted to crush the material supplied immediately before said material is applied to said rotating track for pulverization.

3. In an improved mill as claimed in claim 1, the arrangement of the balls between the two said tracks so that the aggregate of the spaces between the several balls is approximately equal to the diameter of one ball.

EDWARD WILLIAM GREEN.
